ATTORNEY.

UNITED STATES PATENT OFFICE.

HAROLD S. HULL, OF NEW YORK, N. Y.

DESIGN FOR A TABLE COVER OR SIMILAR ARTICLE.

Application filed March 11, 1927. Serial No. 21,110. Term of patent 3½ years.

To all whom it may concern:

Be it known that I, HAROLD S. HULL, a citizen of the United States, residing in the borough of Manhattan, city, county, and State of New York, have invented a new, original, and ornamental Design for Table Covers or Similar Articles, of which the following is a specification, reference being had to the accompanying drawing, forming part thereof.

The figure of drawing is a view in top plan of a table cover or similar article embodying my new and ornamental design.

The design is multi-colored and in most part consists of the natural colors of the flowers represented. The predominating colors of the border and circular and central figures are crimson and violet.

I claim:

The ornamental design for a table cover or similar article, as shown and described.

HAROLD S. HULL.
